CONTAINER CLOSURE

Olof G. Dahlin, Stockholm, Sweden, assignor to AB Orga, Stockholm, Sweden, a corporation of Sweden, and Uno Lindholm, Stockholm, Sweden

Application February 1, 1951, Serial No. 208,967

5 Claims. (Cl. 222—521)

The present invention relates to a closure for containers for powders, liquids and pastes. More particularly, the invention embodies a closure having a cap and a nozzle which can be used with tubes for tooth pastes and powders, creams, and the like, and by means of which the tube contents may be dispensed without removal of the cap.

The general tube for pastes, powders, and creams has a sealing cap, usually threadable, which must be removed in order to dispense the tube contents. In addition to being generally inconvenient, the cap often rolls out of the user's hand onto the floor, or is misplaced, thus adding to the user's annoyance.

It is an object of my invention to present a closure for a tube containing toothpaste and the like in which the tube contents may be dispensed without necessitating removal of any part of the closure.

It is a further object of the invention to present a closure for a tube which is easily manipulated.

Because it is no longer necessary to remove the cap in order to dispense the contents of the tube, one advantage of my invention is that the cap cannot be misplaced or lost.

Another advantage flowing from my invention is that the user need employ only one hand to dispense the contents of the tube.

Other advantages and objects of the present invention will become more apparent as it is described in detail below with particular reference to the accompanying figures.

Fig. 1 is a vertical cross-section of a closure device embodied in my invention;

Fig. 2 is a vertical cross-section of the closure shown in Fig. 1 and taken at 90° thereto, the closure being in open position;

Fig. 3 is a vertical cross-section of a modified form of the closure device;

Fig. 4 is a vertical cross-section of the modified form shown in Fig. 3 and taken at 90° thereto, the closure being in open position;

Fig. 5 is a perspective view of a nozzle employed in the invention;

Fig. 6 is a view in partially broken away elevation of still another form of the invention;

Fig. 7 is a vertical cross-section of the closure shown in Fig. 6 and taken at 90° thereto, the closure being in open position; and,

Fig. 8 is a view in section taken on lines 8—8 of Fig. 6, and looking in the direction of the arrows.

In accordance with the present invention, I have designed a closure for containers dispensing liquids, pastes and powders, which closure comprises a cap having an upwardly converging channel therein and a threaded portion, adapted to cooperate with a threaded portion of the neck of the container, and a nozzle positioned in the neck of the container, which nozzle when the closure is in sealed position extends upwardly into the converging chan-

2

nel so as to engage the channel at its narrowest point only.

With particular reference to the accompanying figures, Fig. 1 shows a portion of a container 11 having a neck portion 12, threaded on its external surface 13. The top surface 14 of the neck 12 projects inwardly of the neck to form the flange 15. A passage or channel 16 in the neck 12 leads to the main body of the container 11.

The cup-shaped cap 17 has an upwardly converging channel 18 which opens out onto the top surface 19 of the cap. The inner surface 20 of the cap 17 has a threaded portion 21 which is designed to cooperate with the externally threaded portion 13 of the container neck 12.

An external flange 22 on the cap 17 serves as a hand grasp for unscrewing the cap and opening the closure.

A nozzle 23 which seats in the container neck 12 cooperates with the cap 17 to seal the container against outflow of the contents. This nozzle 23 comprises flexible arms 24 which extend downwardly from the head portion 25. The top surface 26 of the head portion 25 has the same dimensions as the narrowest point of the channel 18. Although the narrowest point of the channel 18, as shown in, Fig. 1 occurs at its opening in the top surface 19 of the cap 17, it also may occur inside the channel without affecting the invention. This head portion 25 has a downwardly diverging frustum shaped surface 27. When the nozzle 23 is received into the channel 18, the container 11 is closed.

The flexible arms 24 have external lugs 28 positioned thereon. The shoulders 29 of these lugs 28 engage the inner surface 20 of the cap 17 when the closure is in closed position. The bases 30 of the lugs 28 rest on the top surface 14 of the neck 12.

Each of the flexible arms 24 has an external horizontal groove 31 adapted to receive or seat the inwardly projecting flange 15. The flange 15 holds the nozzle 23 in place and prevents the lower portions of the arms 24 from slipping out of the passage 16 in the neck 12. The side openings 32 formed by the arms 24 exit into the annular passage 33 located between the inner surface 20 of the cap 17 and the nozzle 23.

The apex angle of the frustum formed by surface 27 of the nozzle 23 is smaller than the apex angle of the frustum formed by the upwardly converging channel 18. In other words, when the head 25 is received into the channel 18, the corresponding frustum shaped surface of each will engage each other in sealing fashion only near the opening of the channel, i. e. the narrowest point. Thus, an annular space 34 is left between the surface 27 and the lower portion of the channel 18 since the channel is not completely plugged up.

Even in the closed position, my closure has a continuous passage connecting the channel 18 and the body of the container 11. The passage is formed as follows. The passage 16 in the neck 12 connects with the side openings 32 which open out into the annular passage 33. In turn, the annular passage 33 leads into the upwardly converging channel 18 of the cap 17. However, since the cap 17 is in closed position, the channel 18 is sealed by the head portion 25 of the nozzle 23 so that no material may flow through this continuous passage.

The operation of the present invention takes place as follows. When it is desired to open the container and remove some of the powder, paste or liquid therein, the cap 17 is partially unscrewed from the neck 12. This manipulation elevates the cap 17 and unplugs the channel 18 so that material can flow through the continuous passageway formed by the various channels and openings. The container is then squeezed or inverted, which ever may be necessary, in order to dispense the contents thereof. The contents will flow, as shown by the arrows

in Fig. 2, through the passage 16 and between the flexible arms 24 into the side openings 32. The material will then move from the side openings 32 into the annular passage 33, and from there out through the channel 18.

If the further contents of the container are no longer needed, the cap 17 is screwed downwardly into the closed position. The uppermost portion of the downwardly diverging surface 27 will then contact the uppermost portion of the channel 18 thereby sealing the channel against any further outflow.

Any material adhering to the surface of the channel 18 or the surface 27 of the nozzle 23 will be forced into the space 34 by the downward movement of the cap 17. Thus, there will be no mashing or grinding of the surface 27 by material caught between the two surfaces.

At the same time, since the head portion 25 of the nozzle 23 has a different conical apex angle than that of the channel 18, the opening of the channel 18 in the cap 17 will conform to any irregularities in the sealing surface 27 of the nozzle 23 to form an excellent seal.

Moreover, the head portion 25, if the cap 17 should be too vigorously closed, is further protected against mashing or squeezing by the channel surface by means of the shoulders 29 of the lugs 28. These shoulders 29 will engage the inner surface 20 of the cap 17 and prevent the cap from being screwed down further onto the neck 12 with accompanying injury to the nozzle 23.

Furthermore, the thread angle of the neck 12 and the cap 17 is great enough to permit a maximum opening in the channel 18 by a quarter or third turn of the cap.

Figs. 3 and 4 show another form of the closure embodied in my invention. The nozzle 23 is the same as that employed in the closure shown in Fig. 1. However, the cup-shaped cap 17 differs from the cap shown in Fig. 1 in that it has an inner cylindrical sleeve 35 inserted in the cap and affixed thereto, the upper portion 36 of the sleeve being threaded to cooperate with the threaded portion 13 of the neck 12. The sleeve 35 has an inwardly projecting element 37 such as a flange.

The neck 12 has a peripheral rib 38, or some other outwardly projecting element, positioned between the threaded portion 13 of the neck 12 and the shoulder 39 of the container 11.

In unscrewing the cap 17 to open the closure, the cap 17 can not be removed from the container 11 because the rib 38 engages the flange 37 and locks the cap against further upward movement.

When the cap 17 is screwed downwardly into closed position, the rib 38 engages the threaded portion 36 so that further downward movement of the cap is resisted. At the same time, the flange 37 engages the shoulder 39 and also resists further downward movement of the cap 17. Both these features serve to prevent any mashing or destruction of the nozzle 23 by the cap 17 in its downward movement.

Although the sleeve 35 is shown in Figs. 3 and 4 as an element distinct from the cap 17, both elements may be made as one integral part without effecting the present invention.

Any suitable material may be utilized for the nozzle 23 which is flexible enough to permit the arms 24 of the nozzle 23 to move inwardly when the nozzle is inserted in the neck 12, and then to spring back into normal position once it is seated in the neck 12. Furthermore, the cap 17 should be of a softer material than the nozzle 23 or the nozzle should be softer than the cap to obtain the best sealing effect.

A still further modification embodied in the present invention is shown in Fig. 6, in which the nozzle element employed is made an integral part of the container. The cap employed is essentially the same as that shown in Fig. 1. The container 40 has a shoulder 41 and an outwardly threaded neck 42 from which a nozzle 43 extends upwardly and outwardly. This nozzle 43 has a head portion 44 which is joined to the neck 42 by means of

the vertical elements 45 so that the nozzle is an integral part of the neck. Side openings 46, formed by the elements 45, connect the passage 47 in the neck 42 with the annular passage 48 formed by the sides of the cap 49 and the nozzle 43. The annular passage 48 leads into an upwardly converging channel 50 which opens in the top of the cap 49. The head portion 44 of the nozzle 43 fits into the channel 50 but engages only the narrowest part of the channel to produce a sealing effect. The apex angle of the head portion 44 is smaller than the apex angle of the channel 50 to produce an efficient seal.

When the cap 49 is screwed onto the neck 42 by means of a threaded portion 51, its further downward movement will be resisted by the shoulder 41 of the container 40, thereby preventing injury to the head portion 44 of the nozzle 43.

When the closure is opened and the material is being dispensed, the contents will move upwardly through the passage 47, through the side openings 46 into the annular passage 48, around the head portion 44 of the nozzle 43, and out through the channel 50.

While the invention has been described in detail and shown with respect to the accompanying drawings, it is not to be limited to such details, since many changes and modifications may be made in the invention without departing from the spirit and scope thereof. For example, the nozzle of the closure shown in Fig. 3 may be made an integral part of the container rather than an insertable member.

Hence, it is desired to cover any and all forms and modifications of the invention which may come within the language and scope of any one or more of the appended claims.

I claim:

1. A dispensing tube for pastes, powders and liquids including, in combination, a neck portion having an inwardly projecting flange, a cup-shaped cap for said neck portion having a downwardly projecting flange and an upwardly converging channel, and a nozzle element insertable in said neck portion and having a head portion projecting upwardly from said neck portion and fitting into said channel, said nozzle element having flexible arms projecting downwardly into said neck portion and engaging the interior walls thereof, each said arm having an external horizontal groove, said flange being confined within said grooves and serving in conjunction therewith as a connection between said flexible arms and said neck portion to hold said nozzle in position, and abutment means located wholly without the confines of said upwardly converging channel for limiting longitudinal displacement of said cap.

2. A dispensing tube for pastes, powders and liquids including, in combination, a neck portion having an inwardly projecting flange, a cup-shaped cap having a downwardly projecting flange and an upwardly converging channel, said cap and neck portion having cooperating threaded surfaces, and a nozzle element insertable in said neck portion and having a head portion converging upwardly from said neck portion and fitting into said channel, said channel converging at a greater angle than said head portion, said nozzle element and said channel cooperating with each other to seal said channel, said nozzle element having flexible arms projecting downwardly into said neck portion and engaging the interior walls thereof, each said flexible arm having an external groove, said flange being confined within said grooves and serving in conjunction therewith as a connection between said flexible arms and said neck portion, and a plurality of outwardly and downwardly projecting lugs carried by said nozzle element at points intermediate said head and said grooves and seated on top of said neck portion and there serving to retain said nozzle element against longitudinal displacement incident to moving said cap into closing engagement with said head portion.

3. A closure for a container having an inwardly extending ridged neck portion by way of which are dispensed liquids, pastes and powders comprising a cap having an upwardly converging channel, said neck portion and said cap having cooperating threaded surfaces, and a nozzle element insertable in said neck portion, said nozzle element received into said channel in sealing fashion and adapted to engage said channel only at its narrowest point, said nozzle further having flexible downwardly extending elements which seat in said neck portion, each said downwardly extending element having an externally grooved surface which receives said ridged neck portion to retain said nozzle in said container, and abutment means located wholly without the confines of said upwardly converging channel for limiting longitudinal displacement of said cap.

4. A container having a neck portion by way of which are dispensed liquids, pastes and powders, and a closure for said container, said closure comprising a cap displaceably connected to said neck portion for axial movement thereon and having an upwardly converging channel, and a nozzle carried by said neck portion and having a head portion converging upwardly from said neck portion at a greater angle of convergency than that of said channel and adapted to enter said channel and there afford substantially only a line-contact engagement with the wall of said channel, whereby said channel is closed against undue delivery of the container content by way of said channel, a single shoulder on the neck portion of the container, and abutment means cooperable and engageable with said single shoulder and located wholly without the confines of said upwardly converging channel for limiting longitudinal displacement of said cap in opposite directions.

30

5. A container having a neck portion by way of which are dispensed liquids, pastes and powders, and a closure for said container, said closure comprising a cap displaceably connected to said neck portion for axial movement thereon and having an upwardly converging channel, a nozzle carried by said neck portion and having a head portion converging upwardly from said neck portion and adapted to enter said channel and there afford a closure for said channel, said nozzle forming with said cap an annular passage and having a side opening and a central passage by way of which side opening and central passage communication is afforded between said annular passage and the interior of said container, a single shoulder on said cap, and abutment means cooperable and engageable with said single shoulder and located wholly without the confines of said upwardly converging channel for limiting longitudinal displacement of said cap in opposite directions.
